United States Patent Office

Des. 188,553
Patented Aug. 9, 1960

188,553

HANDED CONTAINER

Earl S. Tupper, Smithfield, R.I., assignor to Tupper Corporation, North Smithfield, R.I., a corporation of Delaware

Filed Sept. 3, 1958, Ser. No. 52,487

Term of patent 14 years

(Cl. D44—1)

FIG. 1

I claim:

The ornamental design for a handled container, substantially as shown.
